UNITED STATES PATENT OFFICE.

JAMES H. JENSEN, OF BRIGHAM, UTAH.

SHAFT-HOLDER.

No. 892,058.

Specification of Letters Patent. Patented June 30, 1908.

Application filed August 17, 1907. Serial No. 388,977.

To all whom it may concern:

Be it known that I, JAMES H. JENSEN, a citizen of the United States, residing at Brigham city, in the county of Boxelder and State of Utah, have invented new and useful Improvements in Shaft-Holders, of which the following is a specification.

This invention relates to shaft hangers; and it has for its objects to provide a device of simple and improved construction whereby a line shaft may be supported for rotation, and which shall admit of lateral as well as vertical adjustment of the boxing which constitutes the shaft therein after the hanger has been secured in position, thus enabling inaccuracies to be corrected and the shaft to be supported without being exposed unnecessarily to friction; further objects being to simplify and improve the construction and operation of this class of devices.

With these and other ends in view which will readily appear as the nature of the invention is better understood, the same consists in the improved construction and novel arrangement of parts which will be hereinafter fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the claims may be resorted to when desired.

In the drawing:—Figure 1 is a side view of a shaft hanger constructed in accordance with the invention. Fig. 2 is a front view of the same. Fig. 3 is a transverse sectional view enlarged taken through the bearing box of the hanger. Fig. 4 is a vertical sectional view taken through the supporting device.

Corresponding parts in the several figures are denoted by like characters of reference.

The improved hanger includes a bifurcated bracket member or yoke 1 adapted to be bolted or otherwise secured upon the under side of a ceiling or supporting member such as a beam 2. The bracket 1 is provided with a vertical screw threaded aperture 2 for the passage of a bolt 3 upon which, adjacent to the head 4 at the lower end thereof, there is

loosely supported a sleeve 5 having a laterally extending externally threaded arm 6. The sleeve 5 is secured upon the bolt 4 by means of a clamping nut 7; and a lock nut 8 fitted upon the bolt adjacent to the lower end of the bracket 1, serves to secure said bolt in any position to which it may be adjusted.

The externally threaded arm 6 that extends laterally from the sleeve 5 is provided with clamping nuts 9—9 engaging the ends of a sleeve consisting of a type section 10 which is thereby adjustably mounted upon the arm 6, as will be best seen by reference to Fig. 3 of the drawings. The bearing box 11 is provided on its under side with a collar 12 exteriorly engaging the sleeve 10 upon which the bearing box will thus be mounted in such a manner as to be capable of a rocking or oscillatory motion which will enable the said bearing box to seek its proper position in true axial alinement with the shaft supported therein, thus enabling such shaft to revolve freely within the bearing box.

It will be readily seen that by loosening the lock nut 8 and the clamping nut 7, the bolt supporting the sleeve 5 which in turn supports the bearing box may be moved up or down, thus effecting the desired vertical adjustment of the shaft bearing; lateral adjustment of said bearing being effected by adjusting the supporting sleeve 10 upon the arm 6. By tightening the nuts, the several parts may be readily secured in adjusted position, as will be readily understood. This improved device, as will be seen, is extremely simple; and it permits a delicacy of adjustment which is highly efficient in supporting the shaft without vibration, and in reducing friction to a minimum.

Having thus described the invention, what I claim as new, is:—

The herein described shaft-hanger comprising a detachable supporting bracket having a screw threaded aperture, a bolt engaging said aperture, said bolt having a head at the lower end thereof, a sleeve loosely engaging the bolt and seated upon the head, a clamping nut engaging the upper face of the sleeve, a lock nut fitted upon the bolt adjacent to the lower end of the bracket, said sleeve having a laterally extending externally threaded arm, a bearing sleeve mount-

ed upon the laterally extending arm, a collar mounted upon the bearing sleeve, a bearing box mounted upon the collar, nuts upon the arm and contacting with the end faces of the sleeve and collar for securing the latter upon the arm, said bearing box being mounted for oscillation upon the arm.

In testimony whereof I affix my signature in presence of two witnesses.

JAMES H. JENSEN.
